MULTIPLE PURPOSE GOLF TOOL

Raymond L. Yaudes, P.O. Box 912,
Stephenville, Tex. 76401

Filed Aug. 6, 1973, Ser. No. 386,055

Term of patent 14 years

Int. Cl. D21—02

U.S. Cl. D34—5 CB

Fig. 1

Fig. 2

Fig. 3

Fig. 4

FIG. 1 is an isometric view of the top, front and left end of the multiple purpose golf tool of my original design.

FIG. 2 is an isometric view of the bottom, rear and right end of the multiple purpose golf tool of FIG. 1.

FIG. 3 is an end view of the left end of the multiple purpose golf tool of FIG. 1.

FIG. 4 is an end view of the right end of the multiple purpose golf tool of FIG. 1.

I claim:

The ornamental design for a multiple purpose golf tool, as shown.
